CLAIM

The ornamental design for a flat telephone holder with curved adhesive mount, as shown and described.

DESCRIPTION

FIG. 1 is a perspective view of the flat telephone holder with curved adhesive mount;

FIG. 2 is a top view of the flat telephone holder with curved adhesive mount shown in FIG. 1;

FIG. 3 is a front view of the flat telephone holder with curved adhesive mount shown in FIG. 2 the rear being a mirror image thereof;

FIG. 4 is a bottom view of the flat telephone holder with curved adhesive mount shown in FIG. 1; and,

FIG. 5 is a left side view of the flat telephone holder with curved adhesive mount shown in FIG. 1 the right side being a mirror image thereof.

The patterned surface treatments schematically depicted throughout the views are continuous about the surfaces on which they are shown.
